ERASER TIPPED PENCIL

John F. Linden, Toronto, Ontario, Canada

Application August 20, 1945, Serial No. 611,578

9 Claims. (Cl. 120—38)

1

The invention relates to improvements in eraser attachments for pencils of the ordinary kind commonly known as "lead" pencils, and comprises certain new and useful improvements in the form of the eraser itself and the method of applying it to the ferrule by which it is attached to one end of a pencil.

The ordinary form of a pencil of this type is composed of a core of marking material, such as graphite or "lead" sheathed commonly in a wooden sheath. The ferrule is usually a hollow metal member attached to an end of the pencil from which the eraser projects.

The major object of the present invention is the provision of a one-piece eraser adapted to project from a ferrule and to completely surround the side wall thereof so as to furnish a large and adequate eraser which will last as long as the pencil itself, and which is simple in construction and inexpensive to manufacture.

Another object of the invention is the provision of an efficient and serviceable method of firmly applying the eraser to the ferrule, and one that can be carried out at low cost in the manufacture of the pencil.

Still another object is the provision of the novel arrangement of means for fastening the eraser element to the ferrule so that it will be effectively secured thereto.

Having recounted the major objects and advantages of the invention, other objects and advantages will become apparent from the ensuing detailed description of the invention as illustrated in the accompanying drawing which forms a part thereof.

In the drawing, Fig. 1 is an elevational view partly in section of an eraser tipped pencil embodying my invention.

Fig. 2 is a cross section on line 2—2 of Fig. 1.

Fig. 3 is a similar view to Fig. 1 but showing the pencil as of a circular cross section and the eraser of a hexagonal configuration.

Fig. 4 is a cross section on line 4—4 of Fig. 3.

Fig. 5 is a further elevational view partly in section of a modification.

Fig. 6 is a view depicting the ferrule supplied with a different form of fastening means for the eraser.

Fig. 7 is a view showing the eraser and pencil of Fig. 1 before the ferrule is pressed into the eraser.

The eraser attachment of the invention is adapted to be applied to a pencil of ordinary form. In the drawing there is shown a conventional type of pencil of which the wooden sheath is denoted

2

at 10. In proceeding in accordance with the invention there is provided a cylindrical metal ferrule 11 securely mounted at its inner end to the outer end of the pencil sheath. Conventional means are preferably used to attach the ferrule to the pencil. The inside diameter of the ferrule is substantially equal to the cross section of the pencil. The projecting outer end 12 of the ferrule forms a socket.

10 The eraser element is a block of erasive material, generally denoted at 13, which is made longer and wider than said socket portion of the ferrule. In the application of the eraser element to the outer end of the ferrule it is fitted over 15 the same to provide a distal end 14 of solid material and an inner end comprised of a central tenon 15 which fits into the socket 12, and an outer part 16 which completely surrounds the socket portion of the ferrule and is axially co-extensive with said tenon. Consequently there 20 is supplied a thickness or band of eraser material extending entirely around the outer end of the ferrule whose longitudinal extent is equal to the portion of the eraser material projecting into 25 the socket. Since the cross-sectional area of the eraser element is greater than that of the ferrule, there is provided an unbroken thickness of material around the ferrule which can be advantageously used and which prolongs the life 30 of the eraser.

The block of eraser material is applied to the pencil by pushing the open end 12 of the ferrule into the material so that it will cut its way 35 therein and embed itself. The annular edge of 35 said outer end serves as a cutting edge in urging the ferrule into the eraser material and the central portion of the material which is annularly severed, enters the socket 12 and seats itself against the adjacent end of the pencil in the 40 form of the central tenon 15. The material of the tenon is under compressive stress and the material around the ferrule is under expansive stress, which frictionally binds the eraser on the ferrule both interiorly and exteriorly of the 45 socket. The uncut free end of the eraser extends away from the outer end of the ferrule and forms a comparatively large and solid mass of material which is integral with the tenon 15 and the encompassing outer band 16.

50 The advantages of an eraser extending completely around the ferrule will be clearly appreciated. The large and solid mass of eraser material available for use is ample for all ordinary requirements during the life of the pencil and 55 is convenient of use. The eraser is of uniform

girth and the surface thereof is uninterrupted from one end to the other.

The eraser may be made of a circular or any other configuration in cross section. In Figs. 1 and 2 there is illustrated an eraser of the present disclosure having a circular girth. In Figs. 3 and 4 the eraser is of a hexagonal form. The novel method of attaching the eraser to the ferrule is advantageous in that the wall of the socket is frictionally gripped, internally and externally, by the rough surfaces of the cut made thereby, and it is obvious that these cooperating surfaces are specially adapted to adhere to any approved adhesive material as may be applied in any preferred manner to aid in securing the socket portion of the ferrule to the eraser. The thus provided dual contact surfaces assure of a maximum of rigidity and resistance to longitudinal withdrawal of the eraser as well as guarding against its becoming fractured or broken in use.

To further aid in the securing of the eraser to the ferrule the socket portion 12 may be supplied with claws, grooves or analogous means.

For instance, in Fig. 5 there is depicted a claw-like element 17 formed in the wall of the socket 12 by means of a prick-punch tool after the eraser is applied. For this purpose the prick tool can be driven through the outer thickness 16 of the eraser material. The hole made in the eraser by the prick tool will close on removal of the tool due to the elasticity of the material. One or more indents can of course be made in the ferrule to produce a desired number of the claws.

The fastening means on the socket 12 may also include a groove as represented at 18 in Fig. 5. The groove is shown as a peripheral indentation and may extend partly or completely around the socket. One or more of such grooves may be used.

In Fig. 6 a different form of groove is shown which is of a spiral form and of a coarse pitch. This groove, which is denoted at 19, preferably has its ends tapered as shown. The spiral groove is fashioned by deforming the socket wall and thus provides a ridge interiorly thereof, which due to the steep pitch readily penetrates the eraser block in forcing the ferrule therein. When the eraser is mounted on the ferrule the ridge offers effective resistance against axial displacement of the eraser.

It will be manifest that my invention provides a highly efficient and serviceable eraser for a pencil and that such changes and modifications of the securing means on the ferrule may be resorted to as come within the scope of the subjoined claims.

What I claim is:

1. An eraser attachment for pencils comprising a block of erasive material, and a ferrule adapted to be secured on one end of a pencil, the outer end of the ferrule adapted to project beyond the end of the pencil being implanted in said block in a manner to provide a central tenon of erasive material tightly frictionally fitted in said outer end of the ferrule and to provide an encompassing band-like thickness of erasive material extending completely around said outer end and tightly frictionally fitted thereon, said block being of greater width than the diameter of said ferrule.

2. An eraser attachment for pencils comprising an eraser element of a substantially hexagonal formation having a greater length than

width and having an inner end providing an inner part and an outer part; and a hollow ferrule having its outer end adapted to project from the pencil to constitute a socket, the inner part of said inner end of the eraser element being formed as a tenon and tightly frictionally fitted in said socket, and the outer part of said inner end being formed as a band tightly frictionally fitted around said socket substantially coextensive with said inner part and integral therewith at the outer end of the eraser element.

3. An eraser attachment for pencils comprising an eraser element of a block formation having an inner end, and a hollow cylindrical ferrule of a substantially uniform diameter having its outer end adapted to project from the pencil, said outer end thereof being press fitted into said inner end of the eraser element to cut its way therein and to provide an inner central portion of erasive material tightly frictionally engaged with the interior surface of said outer end and to provide an outer uninterrupted portion of erasive material extending completely around said outer end and tightly frictionally engaged with the outer surface thereof.

4. An eraser attachment as set forth in claim 1, in which the ferrule is provided with positive fastening means for securing the block thereon.

5. An eraser attachment as set forth in claim 1, in which the ferrule is deformed to form thereon projecting elements for securing the block thereon.

6. An eraser attachment as set forth in claim 1, in which the ferrule is prick punched subsequent to the mounting of the block of erasive material so as to provide claws for positively retaining the block thereon.

7. An erasive attachment as defined in claim 3, in which the outer end of the ferrule is supplied with a spiral groove of a coarse pitch for aiding in retaining the eraser element thereon.

8. An eraser attachment for pencils comprising a block of erasive material, and a ferrule adapted to be secured on one end of a pencil, the outer end of the ferrule adapted to project beyond the end of the pencil being implanted in said block in a manner to provide a central tenon of erasive material tightly frictionally fitted in said outer end of the ferrule and to provide an encompassing band-like thickness of erasive material extending completely around said outer end and tightly frictionally fitted thereon, said block terminating at its outer end with a section of solid and uncut material integrally projecting beyond the outer end of the ferrule, and said block being of greater width than the diameter of the ferrule.

9. An eraser attachment for pencils comprising an eraser element of a block formation having a section constituting an outer end of solid and uncut material integrally with a section constituting an inner end carried by an axially hollow cylindrical ferrule having its outer end adapted to project from the pencil, said outer end of the ferrule being press fitted in said inner end of the eraser element to provide an inner central portion of eraser material tightly frictionally engaged with the inner face of said outer end of the ferrule and to provide an outer uninterrupted portion of eraser material completely surrounding said outer end of the ferrule and tightly frictionally engaged with the outer face thereof.

JOHN F. LINDEN.
